COLLECTION EQUIPMENT FOR SPRAY DRYING APPARATUS

Frank E. Bonner, Dayton, Ohio, assignor to The Commonwealth Engineering Company of Ohio, Dayton, Ohio, a corporation of Ohio

Application November 24, 1952, Serial No. 322,315

4 Claims. (Cl. 226—58)

This invention relates to spray drying equipment and more particularly to equipment useful in connection with the collection of material as it is spray dried.

The primary objective of this invention is to provide a flexible means for the collection and shipment of spray dried material.

Some materials which are spray dried are required to be treated, collected and shipped under conditions of absolute sterility. Such a material is hydrolyzed dextran, a blood plasma volume expander, which in the dry state is a fluffy white powder. It is accordingly an object of this invention to describe collection means for such a sterile powder.

The invention will be more fully understood by reference to the following detailed description and accompanying drawings wherein:

Figure 1 illustrates schematically a conventional spray drying system;

Figure 2 is a view partially in section of an arrangement of a collection means embodying the precepts of this invention;

Figure 3 illustrates a step in the removal of the collection means from the system; and

Figure 4 illustrates the packaged condition of the sterile material.

Referring to the drawings there is indicated at 1 in Figure 1 a spray dryer from which dried material 3 is blown through a first conduit 5 to a receiver 7. Since the dryer 1 operates at conditions of elevated temperature the air passing with the material 3 through conduit 5 is heated to a considerable degree and must be exhausted from the equipment; consequently a blower 9 in a second conduit 11 is normally provided for withdrawal of the hot air to the atmosphere from the otherwise closed system.

Blower 9 in its operation however, together with the effect of the air rushing through the conduits past receiver 7, creates a suction pressure in this receiver; since the materials which have been spray dried are normally fluffy, light materials, a large quantity of the product is drawn through conduit 11 and lost.

This suction pressure necessarily requires that the receiver 7 have substantially rigid walls to resist the outside pressure. Accordingly, heretofore, glass jars or bottles have been employed as the receiver 7. Due to the pressure gradient towards line 11 such jars are not readily completely fillable with dried dextran; further due to the weight and fragility of the container the jars are not normally employable as shipping units and therefore it has been the practice to transfer the jar collected material to flexible sterile bags.

Such bags have not up to now been usable as receivers as the pressure conditions prevailing (Figure 1) cause the bag to collapse thus inhibiting the entry of the dried material thereto and increasing product losses.

The structure set out in Figure 2 illustrates a system for overcoming the disadvantages now present in the art. Thus in Figure 2 there is shown at 10 (see Figure 1

2

also) a third conduit extending downwardly from the outlet of conduit 3, the remainder of the equipment except for receiver 7 being the same as described hereinbefore.

As shown in Figure 2 receiver 7 is replaced by a collector unit having an inner sterilized air-impermeable bag 19, preferably of polyethylene, secured to the third conduit 10 at 14 by twine or other suitable tieing means 22 capable of forming an airtight seal between the throat 20 of the bag and the conduit portion. This air-impermeable bag is also provided at 16 with a second tieing means which may be integral with the bag but which when the apparatus is functioning is free as depicted in Figure 2. The bag 19 may be either horizontally or vertically positioned as desired.

Positioned outside of bag 19 is an air-impermeable shell 18 which may be of rubber, polyethylene, rigid plastic or even metal; where rigid plastic or metal is employed adequate seals must be provided to render the shell 18 airtight. Where this outer shell 18 is of a flexible material, such as polyethylene, stays are provided on the internal periphery to prevent the shell collapse upon application of differential pressures thereto. It is to be noted that where polyethylene is employed the wall thickness and frequency of the supports should be sufficient to resist rupture of this casing.

The supporting structure comprises a ring 25 and a somewhat larger ring 27 interconnected by a plurality of stays 29 shaped to conform to the expanded shape of the outer shell 18.

Accordingly in Figure 2 a metal plate 15 closely engaging the conduit 10 receives thereon a flanged portion 21 of shell 18, and suitable clamping means 17 secure the same in airtight relation; gasket means as required by the rigidity of the members may be employed between the flanged portions and the plate, and between the conduit and plate. Alternatively as indicated in Figure 2 the plate may be welded to the conduit as at 23.

Shell 18 is also provided at 24 with a connection 26 which engages over conduit 28 connected to suction pump 30.

Further as shown in Figure 2 it will be noted that conduit 10 is also provided with a line 32 having a valve 34 and a sample collector 36. Under normal operating conditions with material flowing to bag 19 the opening of valve 34 will cause a sufficiently low pressure in collector 36 for a sample of the material to flow thereto, however since under some flow conditions it may be difficult to fill the collector sufficiently an outer casing 38 may be fitted to a plate having clamping means 40, the arrangement being similar to that of plate 15 and clamps 17. Then with the apparatus operating and a vacuum condition created in the casing 38 through line 42 which is also connected to pump 30 the collector 36 is maintained completely open for receipt of material. This sampling apparatus is accordingly similar to the primary equipment hereinbefore described and is of particular utility where periodic testing for sterility is required.

In the operation of the apparatus with the air and, for example, fluffy dextran flowing through line 3, blower 9 (Figure 1) is operated to withdraw the hot air through line 11. However simultaneously with the blower operation suction pump 30 is actuated to cause a low pressure in the shell 18; this effects a differential pressure between the interior and exterior of the polyethylene or other air-impermeable bag 19 causing the bag to be expanded. The drop in pressure in shell 18 need not generally be great to effect this expansion for under usual operating conditions the pressure within bag 19 will only be slightly less than atmospheric and for satisfactory functioning it is only required that the pressure in the chamber defined

by the bag and shell be somewhat less than that in the bag itself.

Accordingly with pump 30 operating the bag 19 may be readily filled with dextran. Experience indicates that some slight amount of dextran will still pass through line 11 and be lost but the increase in speed of operation due to the use of the flexible inner bag compensates somewhat for this factor.

The increased efficiency stems from the several advantages of the inventive arrangement. Initially, the flexible bag is much easier to mount than the glass jars, and this is the case even though the shell also must be positioned for each cycle. The positioning for filling is relatively simple since it is only necessary to first secure a bag 19 on conduit 10 and then mount shell 18 over the bag and the conduit in secured relation with the latter.

When demounting filled bag 19 it is not necessary to shut off the spray drier first although such action is preferable as atmospheric pressure is then substantially immediately established in the bag. Where sterile material is under process the equipment should be located in a sterile room and under this condition the air entry to the bag will not be detrimental.

Preferably also the operation of pump 30 ceases simultaneously with that of the spray drier; the vacuum shell 18 is then broken at 17 and the shell slipped or expanded down over bag 19 to permit sealing thereof at 16 (Figure 3). In this connection it is to be noted that the bag and shell may have any suitable dimension and degree of expansibility to permit passage of one with respect to the other. Bag 19 may then be untied at 22 and removed from the apparatus; shipment of bag 19 may then be made and no necessity arises for transfer of the material until it is ready for use.

Alternatively in the demounting procedure the spray drier may operate until after pump 30 is cut off, the seal broken at 17 and the twine or string 16 tied. Under this condition some slight loss of material may occur due to the lower pressure on the bag interior but generally the bag is sufficiently filled to overcome this slight defect and the bag will not collapse, since under this condition the air-impermeable bag is under a slight vacuum when string 16 is tied and the possibility of any slight contamination is lessened.

It is to be noted that no necessity need arise for demounting the shell from the pump 30 since the shell 18 and connection 26 may be slid over the conduit 28, and that therefore it is only necessary to connect and disconnect at the plate 15 when producing.

The flexible polyethylene bag material (Figure 4) offers several important advantages. First, it is rendered sterile by simple heating; second, it conforms readily to any shape, and close packing arrangements may be effected for shipping; thirdly, it is strong and chemically resistant, and readily sealable; fourth, it is light in weight; and fifth, is relatively inexpensive since it may be formed from flat sheet material.

Other suitable air-impermeable bag materials however may be employed as, for example, treated fabrics, and materials such as the cellophanes and plastics depending upon the particular purpose. However polyethylene is considered preferable because of its versatility in substantially all respects.

It will be understood that this invention is susceptible to modification in order to adapt it to different usages and conditions and accordingly, it is desired to comprehend such modifications within this invention as may fall within the scope of the appended claims.

I claim:

1. A collection unit and spray drier equipment in combination, a spray drier having a first conduit through which heated air and dried material flow, a second conduit communicable with said first conduit for the exhausting of heated air to the atmosphere, and a third conduit communicable with each of the other two, the said collection unit comprising an inner air-impermeable bag secured over the third conduit, the bag being of a flexible material and expandible, an outer casing defining a spacing with said impermeable bag, and means associated with said casing operable to reduce the pressure in said spacing below that in said bag to make said bag in an expanded condition for receipt of dried material.
- 5 2. A collection unit and spray drier equipment in combination, a spray drier having a first conduit through which heated air and dried material flow, a second conduit communicable with said first conduit for the exhausting of heated air to the atmosphere, and a third conduit communicable with each of the other two, the said collection unit comprising an inner air-impermeable bag secured over the third conduit, the bag being of a flexible material and expandible, an outer pouch having supporting stays and defining a spacing with said air-impermeable bag, and means associated with said pouch operable to reduce the pressure in said spacing below that in said bag to make said bag in an expanded condition for receipt of dried material.
- 10 3. In a spray drier system in which the flow of spray dried material is subjected to a vacuum pressure for the elimination of heated air, a trio of intercommunicable conduits a first one of which is adapted to pass heated air and spray dried material to the other two and a second one of which is adapted to pass heated air to the atmosphere, the third conduit having secured thereto a collection unit for spray dried material comprising an inner air-impermeable bag secured over the third conduit, the bag being of a flexible material and expandible, an outer casing defining a spacing with said air-impermeable bag, and means for removably securing one end of each said bag and casing in airtight relation with the said conduit to permit the atmospheric pressure in said spacing to be reduced below that in said bag to make said bag in an expanded condition for receipt of dried material.
- 15 4. In a spray drier system in which the flow of spray dried material is subjected to a vacuum pressure for the elimination of heated air, a trio of intercommunicable conduits a first one of which is adapted to pass heated air and spray dried material to the other two and a second one of which is adapted to pass heated air to the atmosphere, the third conduit having secured thereto a collection unit for spray dried material comprising an inner air-impermeable bag having a throat defining an opening for air-tight reception on said third conduit, the bag being of a flexible material and expandible, an outer casing having a neck extending over said throat in sealing relationship therewith, said casing and bag defining a spacing therebetween, and means associated with said casing operable to reduce the pressure in said spacing below that in said bag to make said bag in an expanded condition for receipt of dried material.
- 20 5. In a spray drier system in which the flow of spray dried material is subjected to a vacuum pressure for the elimination of heated air, a trio of intercommunicable conduits a first one of which is adapted to pass heated air and spray dried material to the other two and a second one of which is adapted to pass heated air to the atmosphere, the third conduit having secured thereto a collection unit for spray dried material comprising an inner air-impermeable bag having a throat defining an opening for air-tight reception on said third conduit, the bag being of a flexible material and expandible, an outer casing having a neck extending over said throat in sealing relationship therewith, said casing and bag defining a spacing therebetween, and means associated with said casing operable to reduce the pressure in said spacing below that in said bag to make said bag in an expanded condition for receipt of dried material.
- 25 6. In a spray drier system in which the flow of spray dried material is subjected to a vacuum pressure for the elimination of heated air, a trio of intercommunicable conduits a first one of which is adapted to pass heated air and spray dried material to the other two and a second one of which is adapted to pass heated air to the atmosphere, the third conduit having secured thereto a collection unit for spray dried material comprising an inner air-impermeable bag having a throat defining an opening for air-tight reception on said third conduit, the bag being of a flexible material and expandible, an outer casing having a neck extending over said throat in sealing relationship therewith, said casing and bag defining a spacing therebetween, and means associated with said casing operable to reduce the pressure in said spacing below that in said bag to make said bag in an expanded condition for receipt of dried material.
- 30 7. In a spray drier system in which the flow of spray dried material is subjected to a vacuum pressure for the elimination of heated air, a trio of intercommunicable conduits a first one of which is adapted to pass heated air and spray dried material to the other two and a second one of which is adapted to pass heated air to the atmosphere, the third conduit having secured thereto a collection unit for spray dried material comprising an inner air-impermeable bag having a throat defining an opening for air-tight reception on said third conduit, the bag being of a flexible material and expandible, an outer casing having a neck extending over said throat in sealing relationship therewith, said casing and bag defining a spacing therebetween, and means associated with said casing operable to reduce the pressure in said spacing below that in said bag to make said bag in an expanded condition for receipt of dried material.
- 35 8. In a spray drier system in which the flow of spray dried material is subjected to a vacuum pressure for the elimination of heated air, a trio of intercommunicable conduits a first one of which is adapted to pass heated air and spray dried material to the other two and a second one of which is adapted to pass heated air to the atmosphere, the third conduit having secured thereto a collection unit for spray dried material comprising an inner air-impermeable bag having a throat defining an opening for air-tight reception on said third conduit, the bag being of a flexible material and expandible, an outer casing having a neck extending over said throat in sealing relationship therewith, said casing and bag defining a spacing therebetween, and means associated with said casing operable to reduce the pressure in said spacing below that in said bag to make said bag in an expanded condition for receipt of dried material.
- 40 9. In a spray drier system in which the flow of spray dried material is subjected to a vacuum pressure for the elimination of heated air, a trio of intercommunicable conduits a first one of which is adapted to pass heated air and spray dried material to the other two and a second one of which is adapted to pass heated air to the atmosphere, the third conduit having secured thereto a collection unit for spray dried material comprising an inner air-impermeable bag having a throat defining an opening for air-tight reception on said third conduit, the bag being of a flexible material and expandible, an outer casing having a neck extending over said throat in sealing relationship therewith, said casing and bag defining a spacing therebetween, and means associated with said casing operable to reduce the pressure in said spacing below that in said bag to make said bag in an expanded condition for receipt of dried material.
- 45 10. In a spray drier system in which the flow of spray dried material is subjected to a vacuum pressure for the elimination of heated air, a trio of intercommunicable conduits a first one of which is adapted to pass heated air and spray dried material to the other two and a second one of which is adapted to pass heated air to the atmosphere, the third conduit having secured thereto a collection unit for spray dried material comprising an inner air-impermeable bag having a throat defining an opening for air-tight reception on said third conduit, the bag being of a flexible material and expandible, an outer casing having a neck extending over said throat in sealing relationship therewith, said casing and bag defining a spacing therebetween, and means associated with said casing operable to reduce the pressure in said spacing below that in said bag to make said bag in an expanded condition for receipt of dried material.
- 50 11. In a spray drier system in which the flow of spray dried material is subjected to a vacuum pressure for the elimination of heated air, a trio of intercommunicable conduits a first one of which is adapted to pass heated air and spray dried material to the other two and a second one of which is adapted to pass heated air to the atmosphere, the third conduit having secured thereto a collection unit for spray dried material comprising an inner air-impermeable bag having a throat defining an opening for air-tight reception on said third conduit, the bag being of a flexible material and expandible, an outer casing having a neck extending over said throat in sealing relationship therewith, said casing and bag defining a spacing therebetween, and means associated with said casing operable to reduce the pressure in said spacing below that in said bag to make said bag in an expanded condition for receipt of dried material.
- 55 12. In a spray drier system in which the flow of spray dried material is subjected to a vacuum pressure for the elimination of heated air, a trio of intercommunicable conduits a first one of which is adapted to pass heated air and spray dried material to the other two and a second one of which is adapted to pass heated air to the atmosphere, the third conduit having secured thereto a collection unit for spray dried material comprising an inner air-impermeable bag having a throat defining an opening for air-tight reception on said third conduit, the bag being of a flexible material and expandible, an outer casing having a neck extending over said throat in sealing relationship therewith, said casing and bag defining a spacing therebetween, and means associated with said casing operable to reduce the pressure in said spacing below that in said bag to make said bag in an expanded condition for receipt of dried material.
- 60 13. In a spray drier system in which the flow of spray dried material is subjected to a vacuum pressure for the elimination of heated air, a trio of intercommunicable conduits a first one of which is adapted to pass heated air and spray dried material to the other two and a second one of which is adapted to pass heated air to the atmosphere, the third conduit having secured thereto a collection unit for spray dried material comprising an inner air-impermeable bag having a throat defining an opening for air-tight reception on said third conduit, the bag being of a flexible material and expandible, an outer casing having a neck extending over said throat in sealing relationship therewith, said casing and bag defining a spacing therebetween, and means associated with said casing operable to reduce the pressure in said spacing below that in said bag to make said bag in an expanded condition for receipt of dried material.
